CLAIM

The ornamental design for the rattle, as shown and described.

DESCRIPTION

FIG. 1 is a perspective view taken from the top, from, and left side of the rattle embodying our new design;

FIG. 2 is a front elevation view thereof;

FIG. 3 is a rear elevation view thereof;

FIG. 4 is a left side elevation view thereof; the opposite side being substantially a mirror image thereof; and

FIG. 5 is a top plan view thereof;

FIG. 6 is a bottom plan view of the rattle of FIG. 1; and, FIG. 7 is a perspective view taken from the top, front, and left side of a specific further embodiment of the general rattle of FIG. 1, having the head of an owl, in accordance with the present invention.

The broken lines are included for the purpose of illustrating the portions of the rattle that form no part of the claimed design.
